UNITED STATES PATENT OFFICE.

VINCENT C. DE YBARRONDO, OF LOS ANGELES, CALIFORNIA.

AIRSHIP.

1,022,117.

Specification of Letters Patent.

Patented Apr. 2, 1912.

Application filed January 11, 1910. Serial No. 537,546.

To all whom it may concern:

Be it known that I, VINCENT C. DE YBARRONDO, a citizen of the United States, residing at Los Angeles, in the county of Los Angeles and State of California, have invented new and useful Improvements in Airships, of which the following is a specification.

This invention relates to airships, and 10 more particularly to heavier-than-air dirigible airships; and it has for its object to provide improvements in vehicles or apparatus of the character stated which will be superior in point of degree and facility of 15 control, positiveness in operation, rate of speed in travel, stability, lightness and rigidity of plane or frame construction; as well as superior in general efficiency, serviceability, and adaptability to varying conditions incident to use and service.

With the above and other objects in view, the invention consists in the novel provision, construction, formation, combination, association and relative arrangement of parts, 25 members and features, all as hereinafter described, shown in the drawings, and finally pointed out in claims.

In the drawings:—Figure 1 is a top plan view of an airship constructed in accordance with the invention; Fig. 2 is a side elevation of the same partly in longitudinal section for clearness of illustration; Fig. 3 is an enlarged fragmentary sectional view, taken upon the line 3—3, Fig. 1, and looking 35 in the direction of the appended arrows; Fig. 4 is an enlarged vertical transverse sectional view, taken upon the line 4—4; Fig. 2, and looking in the direction of the appended arrows, parts being broken away for clearness of illustration; and, Fig. 5 is a 40 fragmentary plan view of a portion of the construction at the right hand end of Figs. 1 and 2, the same being upon an enlarged scale and being partly in section for clearness of illustration.

Corresponding parts in all the figures are designated by the same reference characters.

Referring with particularity to the drawings, the improved airship shown therein is 50 of the heavier-than-air type of dirigible airships, and is further essentially of the monoplane type, having a main plane A from which is suspended a deck B upon which the operator is carried. The main plane A with 55 the deck B may be considered together to comprise the body of the airship which is

provided at the forward end with propelling means C and at the rearward end with steering means D. The propelling means are operated by a motor or motive means E 60 mounted upon the body or frame of the airship.

e designates controlling means for the propelling means C; and d designates controlling means for the steering means D. 65

F and G designate respectively supplemental planes disposed at opposite sides of the main plane A and of the medial longitudinal plane of the airship body or frame; and f and g designate respectively controlling means for the supplemental planes F and G. 70

H designates a fixed fin or vane which projects upwardly from the airship frame or body. 75

K and L designate respectively a forward and rearward pair or set of adjustable wheeled supports the movement of each of which pairs or sets is opposed by tension means k and l respectively. 80

m designates controlling means for the rearward pair or set of wheeled supports L; and n designates controlling means for the wheels of the rearward pair or set of wheeled supports L. 85

P designates what will be herein termed as aerial brake means, the same acting variably to check or oppose forward or rearward movement of the airship; and p designates controlling means for said brake 90 means P.

The propelling means C are the subject of a divisional application filed by me August 30, 1910, Serial Number 579,689.

A specific preferred form, construction 95 and combination of parts, members and features of an airship embodying the principal parts, members and features above set forth, is as follows:—

The main plane A comprises a longitudinal central portion 6 laterally of which are arranged upwardly diverging or slanting side portions 7 which are of the greatest width in a transverse plane of the main plane which is slightly forward of the 100 medial center of the main plane; said side portions at the widest portions thereof being provided with lateral extensions 8 and 9 respectively which increase in width 105 toward their outer edges and with which the supplemental planes F and G are respectively connected. The main plane A, in- 110

clusive of its central portion 6, its side portions 7 and its lateral extensions 8 and 9, is composed of or comprises suitable frame members 10, both longitudinal and transverse, and preferably tubular in form, over which is stretched a covering or wall 11 of suitable light and flexible material, preferably textile. The supplemental planes F and G are preferably of organization similar to that of the main plane. The deck B is suspended from members of the main frame 10 by supplemental frame members 12, both vertical, transverse and longitudinal; and other supplemental frame members 12 are provided for rigidly uniting the deck B and the plane A, together with the propelling means C, the steering means D, the sets of wheeled supports K and L, and the other members and elements of the apparatus; and further particular reference to the ramified parts of the main frame, which includes the deck and the main plane, will not hereinafter be made.

The two extreme margins of the side portions 7 are connected by a truss or brace 13, which may consist of a cable and turnbuckle, or be of any other particular form; and the same serves to strengthen the main frame transversely and to maintain the general formation of the main plane as above set forth, which involves an upward slanting of the side portions 7 thereof; said side portions projecting oppositely from the central portion 6 in simulation of the positions assumed by the wings of a bird in soaring or sailing.

The supplemental planes F and G are respectively pivotally mounted upon or connected with the lateral extensions 8 and 9 of the main plane, at the forward edge portions thereof, as at 14 and 15 respectively, and are preferably each rectangular and elongated in form; and extensions of their longer sides would cut the median longitudinal plane of the main frame at angles of less than ninety degrees.

The controlling means f and g for the supplemental planes F and G are of the same construction in each instance; and a description of one of the same will apply equally to both. The shaft 14 or 15 by means of which each of the supplemental planes is pivotally supported is provided at its inner end with an angularly directed arm 16. Mounted in suitable bearings upon the main plane A and one of the side portions 7 thereof, and extending transversely of said side portion, is a shaft 17 which is broken intermediately and provided with a knuckle joint 18. At its outer end the shaft 17 is provided with an angularly directed arm 19; and a connecting rod 20 extends between the arms 16 and 19. Fixed to the inner end of the shaft 17 is a lever arm 21 carrying a dog 22 which co-acts with a

toothed sector 23 mounted upon a frame member 10. Pivotal movement of either of the lever arms 21 serves to increase or diminish the deflection of the respective supplemental planes F or G from the geometrical plane of the respective lateral extensions 8 or 9 of the main plane A.

The fixed vane or fin H consists of a triangular plate 24 mounted upon a frame member 10 of the main plane A adjacent to the rearward end thereof, and maintained in position of rectangular projection from the longitudinal central portion 6 of the main plane, in the median geometrical longitudinal plane thereof, by suitable lateral braces 25. The apex portion of the plate 24 is directed away from or upwardly from the longitudinal central portion 6 of the main plane.

The steering means D, which act as a rudder or deflector for the airship as an entirety, comprises a plane 26 which is quadrilateral in form, the longest side or edge thereof being disposed farthest from the main plane A; and the smallest edge thereof being substantially equivalent in extension to the transverse dimension of the longitudinal central portion 6 of the main plane; said plane 26 normally extending in the geometrical plane of said longitudinal central portion 6 and being capable of deflection from said plane by the controlling means d. The formation of said plane 26 is substantially the same as that of the main plane A. The inner edge portion of said plane 26 is provided with a shaft or arbor 27 extending transversely of the plane and provided slightly beyond its center with a sector gear 28. The ends of the shaft 27 are journaled in the spaced arms of a yoke 29 which is bored centrally to receive a sleeve 30 which is fixed thereto by screws or other holding devices 31, as clearly shown in Fig. 3. The sleeve 30 is rotatably mounted in a bearing 32, which with the other parts now being described is included within the controlling means d, carried by the rearward frame member 10 of the main plane A. A shaft 33 is rotatably mounted in the sleeve 30, and carries at its rearward end a bevel gear 34 which meshes with the sector gear 28. The sleeve 30 and its rotatable shaft 33 extend forwardly from the bearing 32 through a similar bearing and terminate respectively forwardly and rearwardly of a bearing 35, arranged substantially centrally of the main frame and the main plane thereof; and the bearing 35 carries a doubly toothed sector 36 with which respectively co-act dogs 37 respectively carried by lever arms 38 and 39 which are respectively fixed upon the shaft 33 and the sleeve 30. Oscillation of the lever arms 38 and 39 respectively will cause deflection of the plane 26 from the geometrical plane of the central

portion 6 of the main plane A, by elevation or depression, and by lateral inclination. The deflection of the nature first stated will cause dipping or rising of the forward end 5 of the airship; and deflection of the other form when combined with deflection of the nature first stated, will cause lateral deflection of the forward end of the airship.

Coming to consideration of the organization 10 of the propelling means C, the same are organized and mounted to the end that the propeller c^1 of the same may be deflected from its normal position in which it acts to cause direct longitudinal movement of the 15 airship, into downwardly, upwardly and oppositely laterally facing positions in which it may act to depress or elevate the forward end of the airship, or to deflect the airship laterally in either direction from a straight- 20 away course. These variations of the operative position of the propeller c^1 are produced through the agency of the controlling means c^1 ; and the same comprise an annulus or wheel 40 from the forward face of which 25 projects a semicircular frame 41 the central portion of which is formed into a bearing 42 for the shaft 43 of the propeller c^1 . The annulus 40 is rotatably mounted within an outer annulus 44, a ball race being pro- 30 vided between the two annuli as clearly shown in Fig. 5 at 45. The outer annulus is provided with oppositely projecting elongated bearings, 46 and 47 respectively. The inner annulus 40 is provided with diamet- 35 rically opposed interior heads 48 which receive loosely oppositely projecting bearings 49 upon a ball 50 with opposite portions of the perimeter of which the heads 48 loosely engage so as to be capable of rotation upon 40 the bearings 49.

The forward end of the main plane A is provided with a bearing 51 which receives rotatably two interior locking clutch members, 52 and 53 respectively, the clutch member 53 being connected with or formed upon 45 a power shaft 54 extended from and actuated by the motive means E. A collar 55 locked to the shaft 54 limits forward longitudinal movement of the clutch member 53. The clutch member 52, entering the bearing 51 from the opposite end, carries at 50 its forward end a fixed yoke 56 the arms of which receive rotatably the respective end portions of bearings 57 projecting oppo- 55 sitely from the ball 50 and rectangularly with respect to the bearings 49. The power shaft 54 extends rearwardly of the main frame through a suitable bearing 58 and is directly connected with the motor E which may be of the hydro-carbon explosive type or of any other suitable nature.

The elongated bearing of the outer annulus 44 is received at its outer end within a segmental keeper 59 forwardly from the forward end of the main frame; said outer end

of said bearing having a suitably rotatably flanged sleeve 60 acting as a bearing within the keeper 59. Outwardly of the keeper 59 a collar 61 is loosely applied to the bearing 47; and a yoke 62 is pivotally connected 70 with the collar 61. A connecting rod 63 extends from the yoke 62 rearwardly to a crank arm 64 the shaft of which is provided with a lever arm 65 mounted upon the main frame adjacent to the lever arms 38 and 39; 75 said lever arm 65 carrying a dog 66 which co-acts with a toothed sector 67 mounted upon the main frame. Oscillation of the lever arm 65 causes longitudinal movement of the connecting rod 63 to move the sleeved 80 end of the bearing within the segmental keeper 59, and causes the propeller c to face laterally of the longitudinal medial axis of the main frame. The swinging movement of the bearing 47 last described, which carries with it in such movement the annuli 40 and 44 and the bearing 46, together with the bearing 42 of the propeller shaft, is permitted by the pivotal mounting of the bearing 46 upon a bracket 68 which ranges forwardly from the forward end of the main frame; the outer end of the bearing 46 being surrounded by a sleeve 69 having split ends pivotally connected with the bracket 68, as at 70'. The outer end of the bearing 46 is provided with a crank arm 70 from which extends rearwardly a connecting rod 71 pivotally connected at its rearward end with a crank arm 72 the shaft of which is fulcrumed upon a supplemental frame member 12 and is provided with a lever arm 73 provided with a dog 74 which co-acts with a toothed sector 75. Oscillation of the lever arm 73 causes the crank arm 70 to rock, 105 causing the consequent rocking or oscillation of the bearings 46 and 47, the annuli 40 and 44 and the bearing 42 of the propeller shaft. By this rocking movement the propeller is caused to face downwardly and upwardly with respect to the longitudinal central portion 6 of the main plane. 110

The propeller c^1 is provided with two-part blades, 76-77, the parts of the blades being relatively spaced slightly to provide for an air space therebetween, whereby the 115 thrust area of the propeller is largely increased, although its total working zone is slightly greater than necessary for the operation of a propeller having one-part or unitary blades. The propeller is set to operate in such manner as to impart the power generated thereby in traction upon the main frame and attendant features.

The pair or set K of adjustable wheeled supports comprises downwardly directed spaced arms 78 connected by a transverse rod 79 pivotally connected with supplemental frame members 12, the arms 78 being suitably braced and fitted with wheels 80. 125 Each of the arms 78 is provided with an an-

gularly rearwardly directed stop finger 81 between the outer end of which and a supplemental frame member 12 extends a contractile spring 82 constituting tension means 5 *k*. Each stop finger 81 normally bears against a curved stop 83 upon a supplemental frame member 12; the stop fingers 81 and stops 83 normally maintaining the arms 78 at a downward and forward inclination 10 from the main frame.

The pair or set *L* of adjustable wheeled supports comprises spaced arms 84 provided with wheels at their outer ends with wheels 85, and rigidly connected by a rod 86 journaled in supplemental frame members 12; the arms 84 being provided with angularly and forwardly directed stop fingers 87 between the outer ends of which and supplemental frame members 12 extend contractile 20 springs 88 constituting the tension means *l*; all in correspondence with the adjustable wheeled supports *K* and the tension means *k* therefor. The stop fingers 87 correspondingly co-act with curved stops 89 upon supplemental frame members. The controlling means *m* comprise a band brake 90 upon the arm-carrying rod 86, in combination with a flexible connection, such as a rope or cable 91, extending forwardly to a crank arm 92 the shaft of which is journaled upon a supplemental frame member 12 and adjacent to the lever arm 73 and which is provided with a co-acting dog and toothed sector 93 similar to those heretofore described. The controlling means *n* comprise a band brake 94 applied to the axle of the wheels 85; in combination with a rope, cable or other flexible connection 95 extending over a guide pulley 96 upon a supplemental frame member 12 and thence to a lever arm 97 journaled upon a supplemental frame member 12 adjacent to the lever arm 92 and provided with a co-acting dog and toothed sector, the latter of which may be integral with the sector of 35 the dog and sector 93. The dogs and sector 93 are not shown in full detail, but are constructed in accordance with the other similar parts above described.

The aerial brake means *P* comprise a triangular framework 99 arranged beneath the deck *B* and connected with supplemental frame members 12; said framework 99 having a lateral extent substantially equivalent with that of the deck *B*, which may consist of a flooring 100 directly supporting the member *E*. An open belt 101 surrounds the triangular framework 99 one side of the latter being arranged in a substantially vertical plane and facing forwardly of the main frame; a portion of said open belt being covered by a sheet or apron 102 having a superficial area substantially equivalent to one side or face of the triangular frame. When 50 normally or inoperatively positioned the sheet or apron 102 extends above the upper

side or face of the frame 99; and is brought into service by the depression of its edge portion forwardly of the forwardly facing side of said frame. To the latter end, the controlling means *p* are employed; and the same consist of a sprocket chain 103 which is trained about a sprocket wheel 104 at one end of a shaft 105 arranged at the lower corner of the triangular framework 99, and about which the belt 101 is trained. The 70 sprocket chain 103 also meshes with a sprocket wheel 106 journaled upon a supplemental frame member 12, adjacent to the lever arm 73, and the shaft of which is provided with a lever arm 107 whereby the sprocket wheels 104 and 106 may be jointly operated to cause the movement of the belt 101 and the sheet or apron 102 thereon.

The operation, method of use and advantages of the improvements in airships constituting the invention will be readily understood from the foregoing description taken in connection with the accompanying drawings and the following statement:— The airship is shown in the drawings in assemblage and relative adjustment of parts and features which adapt the same for straightaway flight after elevation from the earth upon which the entirety is supported by the wheels 81 and 85 of the pairs or sets of adjustable supports *K* and *L*. When flight has been initiated, the course taken by the airship may be varied by altering the working relations of one or more of the main features of the construction through the 85 controlling means therewith associated. Through the controlling means *c*, the propeller *c*¹ may be faced to predetermined degrees upwardly, downwardly or laterally in either direction; and either upward or downward adjustment may be combined with either lateral adjustment for resultant adjustment composite of both manipulations. In adjusting the propeller *c*¹ to cause the same to face upwardly or downwardly, the bearing 46, together with the bearing 47 and the intermediate parts and features, is rocked through the agency of the crank arm 70, the connecting rod 71 and the lever arm 73. Lateral facing of the propeller *c*¹, in either direction, is caused through the agency of the connecting rod 63 and the lever arm 65. In whatever plane of rotation the propeller may be located, such rotation is caused by the rotation of the power shaft 54 which in turn rotates the clutch members 52 and 53, the yoke 56, the ball 50 and the heads 48 which receive the bearings 49 upon the ball 50; the bearing 42 for the fixed shaft 43 of the propeller 90 being thereby rotated. The said rotation takes place as between the annulus 40 and the annulus 44 which are separated by the ball race 45.

The plane 26 of the steering means *D* 120

may be inclined upwardly or downwardly with respect to the longitudinal central portion 6 of the main plane A through the agency of the shaft 33 and the lever arm 38; and said plane 26 may be axially adjusted through the agency of the sleeve 30 and the lever arm 39. Both stated adjustments of the plane 26 may be caused compositely through the controlling means *d* 10 including the lever arms 38 and 39, so that the plane 26 may be caused to act as a rudder to effect the dip or rise or lateral deflection of the forward end of the air ship, which deflections from a straightaway course may be likewise caused or partially produced by the propeller *c* in combination with the controlling means *e*, as above described.

The fixed fin or vane H, consisting of the 20 triangular upwardly directed plate 24, acts to maintain inherent stability of the airship, as against oscillation upon the longitudinal medial axis of the airship; opposing such latter play or gyration under the 25 effect of air pressure upon the vane caused in such axial oscillation. Lateral stability of the airship is also produced or partially effected by the supplemental planes F and G. Tendency of the airship to dip laterally 30 in either direction, or to rock upon a longitudinal axis, may be opposed by varying the inclination of the proper supplemental plane, through the agency of the respective controlling means *f* and *g* and the respective lever arm 21 thereof, so that the air pressure 35 upon such supplemental plane, above or beneath the same, shall be partly increased or diminished. Likewise, said supplemental planes F and G may be adjusted in substantially vertical positions in which they will 40 act as aerial brakes to retard or check further rearward movement of the airship.

The main plane A, including the side portions 7 and lateral extensions 8 and 9, comprise 45 the main sustaining surface formation, bearing the entire apparatus aloft by translation of the impingement of the air currents thereupon into supporting energy.

The forward or rearward movement of the 50 airship may be effectively retarded or checked by the aerial brake means P, the sheet or apron 102 carried by the open belt 101 which may be to varying degrees projected downwardly beneath the deck B so as to be opposed to the air wall and to the rearwardly rushing air currents generated by the propeller *c*. The crank arm 107 of the controlling means *p* serve to determine the 55 position of the sheet or apron 102 with respect to its utilization or nonutilization as set forth.

The wheeled supports, or sets of the same, K and L, resiliently or yieldingly bear the 60 entire weight of the airship, when the latter is at rest; as it will be manifest that the

springs 82 and 88 will permit the rods 79 and 86 with which the wheel-carrying arms 78 and 84 are connected to rock. Thus, when the airship is alighting, the inertia of the descent will be yieldingly opposed and neutralized by the tension means *k* and *l*; the wheeled supports K and L giving respectively forwardly and rearwardly, as well as downwardly. This rearward and downward yield or give of the wheeled supports L may 70 be checked or opposed by the controlling means *m* consisting of the band brake 90 and the lever arm 92 connected with the same. Likewise, movement of the airship along the ground upon its wheeled supports may be checked or retarded by the controlling means *n* consisting of the band brake 94 applied to the axle of the wheels 85, together with the lever arm 97 connected with said band brake.

It will be noted that the several controlling means *c*, *d*, *f*, *g*, *m*, *n*, and *p*, all include members which are grouped together substantially centrally of the airship main frame, in convenient position for manipulation by the operator who is stationed upon the deck B. Thus, the levers 65 and 73 of the controlling means *c*, the levers 38 and 39 of the controlling means *d*, the lever arms 21 of the controlling means *f* and *g*, the lever arms 92 and 97 of the controlling means *m* and *n*, and the lever arm 107 of the controlling means *p* are all grouped together in positions which enable convenient manipulation by the operator of the airship. The lever arms 92 and 97, and the lever arm 107, are in relatively low positions wherein they may be reached and actuated by the feet of the operator.

The airship as organized and constructed, in accordance with the invention, is designed and adapted to efficiently meet, utilize and neutralize the various favorable and adverse conditions of service met with in a wide variety of the latter, both in starting, flight, and coming to rest upon return to the earth; and the various leading features of design and construction provide for effective control of the airship with respect to course of travel and ascent and descent.

I do not desire to be understood as limiting myself to the specific provision, construction, combination, association and relative arrangement of parts, members and features shown and described; but reserve the right to vary the same, in adapting the improvements to varying conditions of use, without departing from the spirit of the invention and the terms of the following claims.

Having thus described my invention, I claim and desire to secure by Letters Patent:

1. In an airship, a main plane comprising a longitudinal central portion and lateral portions each of which is of varying width and provided at its widest portion with a

lateral extension which increases in width toward its outer edge.

2. In an airship, a main plane comprising a longitudinal central portion and lateral portions each of which is of varying width and provided at its widest portion with a lateral extension which increases in width toward its outer edge; each of said lateral extensions being provided with a movable supplemental plane.

3. In an airship, a main plane, a bearing thereon, a sleeve rotatable in said bearing, a yoke fixed to said sleeve, a supplemental steering plane pivotally mounted in said yoke, a gear connected with said steering plane, a shaft rotatable in said sleeve, a gear upon said shaft meshing with said gear upon said steering plane; means for rotating said sleeve, and means for rotating said shaft.

4. In an airship, a main plane, a bearing thereon, a sleeve rotatable in said bearing, a yoke fixed to said sleeve, a supplemental steering plane pivotally mounted in said

yoke, a gear connected with said steering plane, a shaft rotatable in said sleeve, a gear upon said shaft meshing with said gear upon said steering plane; means for rotating said sleeve, and means for rotating said shaft; each of said rotating means being provided with a controlling lever, and said levers being arranged in juxtaposition.

5. An airship provided with an adjustably supported flexible body, and means for presenting varying portions of the superficial area of the same directly in opposition to the air to check the motion of the airship; said supplemental frame being triangular in form and provided with an endless belt upon which said sheet or apron is mounted.

In testimony whereof, I have signed my name to this specification in the presence of two subscribing witnesses.
